UNITED STATES PATENT OFFICE.

WILLIAM R. FOX, OF GRAND RAPIDS, MICHIGAN.

TYPE-WRITING MACHINE.

1,177,943.

Specification of Letters Patent.

Patented Apr. 4, 1916.

Application filed December 29, 1913. Serial No. 809,164.

To all whom it may concern:

Be it known that I, WILLIAM R. FOX, a citizen of the United States, residing at Grand Rapids, Michigan, have invented certain new and useful Improvements in Type-Writing Machines, of which the following is a specification.

This invention relates to improvements in typewriting machines.

10 The objects of this invention are: First, to improve the key action and lever connections of front-strike typewriting machines. Second, to provide an improved combination whereby the work done by the key and key lever is so distributed that the action of the escapement can be made very easy and with the type at a minimum distance from the printing point. Third, to distribute the load on the key lever so that the best effect and 20 stroke can be given to the type bar. Fourth, to separate the ribbon shift means from the escapement means so that the action of the escapement shall be easy and also so that the ribbon shift will be actuated to move the 25 ribbon to printing position by the force of the full stroke upon the key in advance of the escapement.

Further objects and objects relating to details and economies of construction and operation will definitely appear from the detailed description to follow.

I accomplish the objects of my invention by the mechanism described in the following specification. The invention is clearly defined and pointed out in the claims.

A structure embodying the parts of a front-strike typewriter included and involved in my invention is clearly illustrated in the accompanying drawing, forming a 40 part of this specification, in which:

Figure I is a detail longitudinal sectional elevation view through the central part of a typewriter, showing the key lever and connection, the universal escapement bar and the ribbon shift connections, partly in section lines, with a single key lever and type bar and connections in position, the shifting type segment being in lower case position. Fig. II is a plan view of the structure appearing in Figs. I and IV, the platen roll being omitted. Fig. III is a detail sectional elevation view on line 3—3 of Fig. II, showing the escapement universal bar and connections, and the means of supporting and guiding the same detached from the type bar segment. Fig. IV is a detail perspective view

of these parts detached from the machine. Fig. V is a detail longitudinal sectional view corresponding to the view appearing in Fig. I, the type bar segment being shifted to the elevated or upper case position and the key lever and certain parts being partially indicated by dotted lines in depressed position. Fig. VI is a detail perspective view of the escapement push rod with its head. Fig. VII is a detail perspective view of the rocker for controlling the ribbon shift.

In the drawings, all of the sectional views are taken looking in the direction of the little arrows at the ends of the section lines, and similar numerals of reference refer to similar parts throughout the several views.

Considering the numbered parts of the drawing, I desire to state that my invention here illustrated is adapted to the well known Fox typewriter. The frame 1 is the frame of that machine, the details of which I have not deemed it necessary to illustrate, as my invention does not relate particularly to the frame structure.

2 is the cross bar key lever stop against which the key levers are raised in the machine. Key levers 3 are provided with buttons 4 at the front and are fulcrumed at 5 at the rear. Each key lever, one only of which is illustrated, is provided with a horizontal forward projecting finger 6 to engage and operate the corresponding rock lever 10, which has a rearwardly projecting arm 9 provided with a curved contact surface, which in Fig. I is shown contacted toward its rear end with the engaging finger 6 of the key lever, and in Fig. V, where the same is, by the dotted line, shown depressed, the contact is well toward the front end of the projecting finger 6.

This secures a powerful action on this arm 9 to start the same and overcome the inertia of parts and a very rapid movement on the further depression of the key, which is highly desirable, as it requires a strong action to overcome the inertia, and a rapid movement to follow up after the initial impulse to the type bar. The key lever contact may be curved instead of the rock lever and secure the same result. Guide fingers 3' are preferably punched from the metal of the key lever to retain the arm 9 in the engaging position.

The rock levers 10 are fulcrumed at their central portion 7 on the rod 8 and are provided with upwardly projecting hooks 11

which are engaged by springs 12 that are connected to suitable devices on the frame to put tension on the same and insure the prompt return of all the parts to the initial position.

5 Each type bar 16 is fulcrumed at 16' on a suitable hanger 7, which is carried on the type segment 18. This type segment is shiftable up and down to take care of the 10 upper and lower case letters as is common in the Fox typewriter construction. A top coupler 14 is connected by pivot 13 to the upper end of the rock lever 10 and to the actuating pivot 15 of the type bar 16. It 15 will thus be seen that when the key lever is depressed the type bar is started with powerful action and is rapidly followed up until the type strikes the platen.

20 The type bar is notched at 19 close to its fulcrum 16', and is there adapted to strike the universal bar 20 which, through its connections and supports, actuates the escapement. This universal bar 20 is carried by a pair of arms 21, 21 projecting from plate 25 22 which is secured by suitable screws through the holes 22' to the back side of the shifting type gate. The universal bar 20 is curved so that the contact notch or projection 19 of each type bar will strike it and move it backwardly. This curved universal 30 bar 20 is secured to bar 24 by suitable rivets 25, 25 through suitable lugs 26, 26,—see Figs. II and IV, and has a forwardly projecting slide 27 disposed through a slot 27' in the plate 22. Rearwardly projecting arms 23, 35 23 are formed on the supporting bar 24 or attached thereto and extend rearwardly and are secured by pivots 28, 28 to the lower end of downwardly extending link 29, 29, which 40 are pivoted at 30, 30 to the rear end of arms 21, 21 at each side. It will thus be seen that any pressure against the universal bar 20 secures a parallel movement of these parts in direct line toward the rear. The parts are 45 very light and compact. A horizontal cross bar 31 extends between the arms 23, 23 and on this is carried an upwardly projecting block or bracket 32, in which is an adjustable thrust pin 34, the position of which is 50 regulated by screw 33 provided with suitable lock nut.

55 A sliding trip pin 36, with an enlarged head 35, is supported in suitable downwardly projecting ears 36' on plate 36' secured to frame 1 of the machine, as clearly appears in Figs. I and V, this support being omitted from Fig. II for the sake of clearness. The object of this broad disk head is to enable the use of a round pin which 60 secures easy action and construction and provides a broad surface for the contact of the thrust pin 34 carried by the universal bar structure, so that, no matter in which position the shifting gate may be, whether 65 it is in the upper or in the lower position,

it will contact with this trip pin and thus properly actuate the escapement.

The escapement shown comprises the usual escapement wheel 38 with the escapement dog mechanism 37, with the lower end 70 of which the trip pin 36 contacts. The usual spring devices are provided to hold the same in intact position.

75 For the ribbon shift, a universal bar 39 is provided, the same being so disposed that the upper ends of the rock lever 10 will strike against the same to secure its actuation, as indicated by full lines in Fig. I, and the dotted lines in Fig. V. This universal bar 39 has a rearwardly projecting horizontal arm 40 which is slotted at 41 and slides freely over the pin 42 which limits and guides its movement. The spring 44 80 puts tension upon this structure and holds it in the forward position. Rearwardly 85 projecting arms 45, 45 are at each side of the universal bar 39, carrying pivots 46 which connect to the tops of arms 47, 47 which are connected to the rocking bar 49 at their lower ends. This rocker is supported on 90 pivots 47' in the holes 47'', which pivots are on the main frame. It will thus be seen that any rearward movement of the universal bar 39 will cause the rocker frame to oscillate. 95

Projecting rearwardly from the cross bar 49 is curved arm 50 provided with a slot 51 extending from the front to the rear thereof, the forward end of the said slot being in line with the pivot 47'. The ribbon oscillator is operated by the rocking of 100 this arm which acts through the link 53 which is provided with a pin 52 engaging in the slot 51 at its lower end connected by pivot 45 at its upper end to the ribbon oscillating lever 55 which is fulcrumed at 56 and is connected by pivot 58 to the oscillating ribbon guide 57, as seen particularly in Fig. I, and the parts being omitted from Fig. II. 105

110 The lower end of the link 53 is controlled by suitable connections to a key on the keyboard whereby its position is shifted in the slot 51, thereby regulating the throw of the ribbon mechanism which is desirable for the 115 purpose of using different parts of the ribbon, also to shift a particolored ribbon, and by moving the pivot 52 to the extreme forward end of the slot 51, all movement of the ribbon oscillator is suppressed, which 120 is desirable in stencil making. I mention this as a feature here because I do not intend to claim it specifically, but to merely indicate the purpose of this particular construction which is operated by my improved key action. In this connection I have illustrated both the escapement and the ribbon shift as operated by means of a single rock lever for and connection to each 125 key lever. The structure shown in this ap- 130

lication can be greatly modified without departing from the spirit of my invention, and I have shown in my companion case, Serial No. 809,165, filed December 29, 1913, 5 one modification in which two rock levers are provided, one for operating the ribbon shift and the other for operating the type bars. I, therefore, do not wish my broad claims to be considered as restricted to a 10 single rock lever, but desire to claim the invention broadly.

A matter of the highest consequence is the entire separation of the escapement mechanism and its universal bar from the 15 ribbon shift mechanism or any other function as part of the type bar or key lever action. By thus separating the same, the action of the escapement, being very light, I am able to secure very prompt action of 20 the escapement by the type bar itself at the end of the stroke, as a matter of fact, this may be within a quarter of an inch of the platen, as I have demonstrated in actual practice with my machine. At the same 25 time, owing to the fact that the ribbon mechanism is controlled independently, the ribbon can be moved very promptly to position on the full stroke of the key, well in advance, of the escapement action, so that 30 the very highest speed of the typewriter will be attainable because the ribbon is in position to print whenever needed, and the escapement occurs at substantially the instant of printing. This matter is highly 35 desirable to secure a clean-cut print and high speed. I desire to claim the mechanism by which I accomplish this result specifically and I also desire to claim the invention broadly, as indicated in the ap- 40 pended claims.

Having thus described my invention, what I claim as new and desire to secure by Letters Patent is:

1. In a typewriting machine, the combination of a suitable key lever, a rock lever with curved end to afford a variable leverage, a ribbon operating universal bar adapted to be acted upon by the said rock lever, a shiftable type bar segment, a type 45 bar with a trip contact in close proximity to the pivot thereof, an escapement universal bar disposed to be acted upon by the said contact of the type bar when it is near the printing point, a parallel movement 50 support for said universal bar on the said type bar segment, a push pin carried by said support, an escapement means, and a sliding trip pin for the escapement mechanism carried on the frame and having a 55 broad head to insure contact of the push pin therewith at all positions of the type bar segment, all coacting substantially as described.

2. In a typewriting machine, the combination of a suitable key lever, a rock lever

operatively connected therewith, a ribbon operating universal bar to be acted upon by the said rock lever, a shiftable type bar segment, a type bar with a trip contact in close proximity to the pivot thereof, an escapement universal bar disposed to be acted upon by the said contact of the type bar when it is near the printing point, a parallel movement support for said universal bar on the said type bar segment, a push pin 70 carried by said support, an escapement means, and a sliding trip pin for the escapement mechanism carried on the frame and having a broad head to insure contact of the push pin therewith at all positions of the type 75 bar segment, all coacting substantially as described.

3. In a typewriting machine, a shiftable type bar segment, a type bar with a trip contact in close proximity to the pivot thereof, an escapement universal bar disposed to be acted upon by said contact of the type bar when it is near the printing point, a supporting frame with rearwardly projecting parallel arms secured to the said type 80 bar segment, downwardly depending links at the rear end of said arm, a frame secured to the said universal bar and connected to the lower end of said links, slidably supported on the said supporting frame, a push pin carried by the said universal bar structure, an escapement means, and a sliding trip pin for the escapement means carried on the frame of the machine and having a broad head to insure contact of the said 85 push pin therewith at all positions of the type bar segment, as described.

4. In a typewriting machine, a shiftable type bar segment, a type bar with a trip contact in close proximity to the pivot thereof, an escapement universal bar disposed to be acted upon by said contact of the type bar when it is near the printing point, means for supporting said universal bar on said type bar segment, a push pin carried by the said universal bar structure, an escapement means, and a sliding trip pin for the escapement means carried on the frame of the machine and having a broad head to insure contact of the said push pin therewith at all positions of the type bar gate, as 90 specified.

5. In a typewriting machine, the combination of a suitable key lever, a rock lever operatively connected therewith with curved 105 end to afford a variable leverage, a ribbon operating universal bar to be actuated by said rock lever, a shiftable type bar segment, a type bar with a trip contact in close proximity to the pivot thereof, an independent 110 universal escapement bar carried by said segment and disposed to be acted upon by said contact of the type bar when it is near the printing point, an escapement, and operative means from said universal bar to 115 120

125

- the escapement, coacting for the purpose specified.
6. In a typewriting machine, the combination of a suitable key lever, a rock lever 5 operatively connected therewith, a ribbon operating universal bar to be actuated by said rock lever, a shiftable type bar segment, a type bar with a trip contact in close proximity to the pivot thereof, an independent universal escapement bar carried by said segment and disposed to be acted upon by said contact of the type bar when it is near the printing point, an escapement, and operative means from said universal bar to 15 the escapement; coacting for the purpose specified.
7. In a typewriting machine, the combination of a suitable key lever, connections therefrom to the ribbon oscillating mechanism, a shiftable type bar segment, a type bar with a trip contact in close proximity to the pivot thereof, an independent universal escapement bar carried by said segment and disposed to be acted upon by said contact of 20 the type bar when it is near the printing point, an escapement, and operative means from said universal bar to the escapement, coacting for the purpose specified.
8. In a typewriting machine, the combination of a suitable key lever, a rock lever 25 operatively connected therewith with curved end to afford a variable leverage, a universal bar to be actuated by said rock lever, a shiftable type bar segment, a type bar with a trip contact in close proximity to the pivot thereof, an independent universal escapement bar carried by said segment and disposed to be acted upon by said contact of 30 the type bar when it is near the printing point, an escapement, and operative means 35 from said universal bar to the escapement, coacting for the purpose specified.
- 40
9. In a typewriting machine, the combination of a suitable key lever, a rock lever one end of which has a curved actuating 45 surface to afford a variable leverage, a shiftable type bar segment, a type bar with a trip contact in close proximity to the pivot thereof, a universal escapement bar carried by said segment and disposed to be acted 50 upon by said contact of the type bar when it is near the printing point, an escapement, and operative means from said universal bar to the escapement, coacting for the purpose specified. 55
10. In a typewriting machine, the combination of a suitable key lever, a rock lever operatively connected therewith, a ribbon operating universal bar adapted to be actuated by the upper end of said rock lever, a shiftable type bar segment, a type bar pivoted therein, a link connecting said type bar with the upper end of said rock lever, said type bar being provided with a trip contact in close proximity to the pivot thereof, 60 an escapement universal bar carried by said shiftable type bar segment and positioned to be acted upon by the said contact of the type bar when it is at or near the printing point, and connections from said 65 universal bar to the escapement mechanism, all coacting substantially as described for the purpose specified. 70

In witness whereof, I have hereunto set my hand and seal in the presence of two 75 witnesses.

WILLIAM R. FOX. [L. S.]
